UNITED STATES PATENT OFFICE.

CHARLES A. DAHL, OF BOSTON, MASSACHUSETTS, ASSIGNOR TO THE REECE BUTTONHOLE MACHINE COMPANY, OF BOSTON, MASSACHUSETTS, A CORPORATION OF MAINE.

BUTTONHOLE-SEWING MACHINE.

No. 911,551.

Specification of Letters Patent.

Patented Feb. 2, 1909.

Application filed November 19, 1908. Serial No. 463,450.

To all whom it may concern:

Be it known that I, CHARLES A. DAHL, a citizen of the United States, residing at Boston, county of Suffolk, and State of Massachusetts, have invented an Improvement in Buttonhole-Sewing Machines, of which the following description, in connection with the accompanying drawing, is a specification, like letters on the drawing 10 representing like parts.

This invention relates to buttonhole sewing machines of the type wherein a needle thread is used in conjunction with an under thread in the formation of the stitches, such 15 as is shown and described in United States Patent No. 862238 granted to me August 6, 1907, and my present invention relates more particularly to the under thread-carrying mechanism of my patent, and has for its object certain novel features of construction 20 whereby the operation and adjustment of the mechanism is much improved and facilitated.

The various novel features of my invention will be fully described in the subjoined 25 specification and particularly pointed out in the following claims.

Figure 1 is a detail in elevation showing a needle, and the circularly movable carrier 30 sustaining the means complementary to the needle making the stitch, with my present invention embodied therein, the parts shown being a sufficient portion of a buttonhole sewing machine to enable my invention to be 35 understood; Fig. 2 is a top plan view of the mechanism shown in Fig. 1; Fig. 3 is a rear elevation of the oscillating support detached, and with the parts usually carried thereby removed; Fig. 4 is a top plan view of the 40 support; Fig. 5 is a perspective view, enlarged, of one of the adjustable stops for the loop spreader, to be described.

In my patent hereinbefore referred to the 45 loop spreaders are pivotally mounted on the oscillating supports and are spring-actuated in one direction and they are moved in the opposite direction by a spreader actuator, and such is the general construction herein, but I have in my present invention pro-

vided means whereby the spring-induced 50 movement of the spreaders can be adjustably limited readily and with great accuracy. This adjustment is of great advantage in enabling me to set the loop spreaders properly and easily with relation to the loopers, 55 and I have so constructed the adjustable spreader stops that they also serve as down-holds to retain the loop spreaders in operative position on the support. I have also provided each spreader with a shaft which is 60 mounted to rock freely in a long bearing in the support, as will be described.

Referring to Fig. 1, the eye-pointed needle *d*, the carrier *48* capable of a circular movement, its longitudinal central shaft *59* having 65 at its upper end a stud screw *109* entering a link *108* connected at its upper end by stud screw *107* with a lever *106* fulcrumed at *105* on the carrier; and the link *113* connected at its lower end at *112* with the lever *106* and 70 at its upper end at *114* with an arm *115* of the oscillating block or support *116*, may be and are in general all substantially as in my 75 said patent, and operate as therein set forth, the support being mounted to oscillate on a stud screw *117*. Herein, however, I have made some changes in the oscillating support *116*, which is of general triangular shape and provided on each of its upwardly divergent sides with a pair of separated arms *120*, 80 *121*, the arm *115* forming an extension of one of the arm *121*, see Fig. 3.

Each pair of arms is drilled to form a long bearing *122*, see dotted lines Fig. 3, the bearings being upwardly divergent, and the upper arms *120* are enlarged to provide room for sockets *123* and holes *124*, best shown in Fig. 4. A thread-carrying looper *30* has its shank inserted in one of the sockets *123* and the other socket receives the shank of a non-thread-carrying looper *31*, substantially as in 90 my patent, the shanks of the loopers being fixedly held in the sockets by suitable set screws, as shown in Fig. 1. The loop-spreaders *32*, *33* co-act respectively with the 95 loopers *30* and *31* and each spreader has an attached, elongated shaft *32*, Fig. 1, which is mounted to rock in one of the long bear-

ings 122, giving a firm and strong support to the spreader in its angular movement when coöperating with the thread. A piece of spring wire is bent around the hub 117^x of the support and its ends are carried upward and rearward, at 125, to bear against the outer ends of the loop spreaders, to swing the latter forward away from the path of the loopers, such spring-induced movement being limited by means to be described. Headed screws 126 on the arms 121 hold the spring in place on the support, this arrangement simplifying the construction of the spring and obviating the use of separate coiled springs as shown in my patent. The loop spreaders are swung or rocked in opposition to the action of the spring by the spreader actuator H, having the arms h, h', as in my patent, and need not be described herein in detail.

The adjustable spreader stop is shown separately in Fig. 5, one of such stops being provided for each spreader, each stop comprising a cylindrical stud 127 having at its upper end a laterally extended stop finger 128 and an overhanging ear or downhold 129. The studs 127 fit into the holes 124 in the upper arms 120 of the support 116 and the stop finger of each stop bears against the front edge 30 of the adjacent loop spreader when the spreaders are at rest, while the downholds 129 overhang the tops of the spreaders, as shown in Fig. 2 and retain the shafts of the latter in their bearings 122 while permitting 35 them to rock freely. The arms 120 are provided with threaded holes to receive set screws 130 to bear against the studs 127 of the spreader stops, the screw holes intersecting the holes 124, so that by setting up the 40 set screws after the stop fingers are in the adjusted angular position said fingers will be fixedly held in such adjustment. By means of the angular adjustment of the stop fingers, the spring-induced movement of the loop 45 spreaders can be regulated with great accuracy, to bring them into the exact relation with the loopers, and the adjustment can be easily and quickly changed as required. It will be seen that ample angular adjustment 50 of the fingers is permitted without at all interfering with the functions of the downholds 129, so that the spreaders will be properly retained in position.

Should it become necessary to replace a 55 loop spreader the set screw of its stop is loosened and the stud is turned far enough to swing the downhold clear of the spreader, whereupon it can be lifted out and another one substituted.

60 In Fig. 1 I have shown a spring-plate 131 fixed at its base to the support 116 and upturned in front of the part of such support between the arms 120, to serve as a needle-guard, the needle passing downward between the face of the support and the back of

the guard into proper position for the loops of thread to be manipulated in the formation of the stitch as the needle rises.

Various changes in details of construction may be made by those skilled in the art without departing from the spirit and scope of my invention as set forth in the claims annexed hereto.

Having fully described my invention, what I claim as new and desire to secure by Letters Patent is:—

1. In under thread-carrying mechanism for buttonhole sewing machines, an oscillating support, a plurality of loopers fixedly mounted thereon, a plurality of spring-controlled loop spreaders pivotally mounted on the support, and an angularly adjustable stop and downhold for each loop spreader to retain the same on the support and limit spring-induced movement of the spreader. 80

2. In under thread-carrying mechanism for buttonhole sewing machines, an oscillating support, a plurality of loopers fixedly mounted thereon, a plurality of spring-controlled loop spreaders pivotally mounted on the support, an angularly movable stud mounted on the support adjacent each loop spreader and having a lateral stop-finger to coöperate therewith, and means to act upon the studs and maintain them in angularly 90 adjusted position.

3. In under thread-carrying mechanism for buttonhole sewing machines, an oscillating support having pairs of separated and aligned bearings, a plurality of loopers fixedly mounted on the support, a plurality of loop spreaders each having an attached shaft mounted to rock in a pair of the separated bearings, and an angularly adjustable stop for each loop spreader, each stop having a 105 downhold overhanging the adjacent loop spreader to retain the shaft thereof in its bearings. 100

4. In under thread-carrying mechanism for buttonhole sewing machines, an oscillating support having upwardly diverging bearings, a plurality of loopers fixedly mounted on the support, a plurality of spring-controlled loop spreaders each having an attached shaft mounted to rock in one of the 115 bearings, a combined downhold and adjustable stop for each loop spreader, and means to retain the stops in adjusted position. 110

5. In under thread-carrying mechanism for buttonhole sewing machines, an oscillating support, a plurality of loopers fixedly mounted thereon, a plurality of loop spreaders pivotally mounted on the support, a bent spring fixedly held on the support and having its free ends coöperating with the spreaders outside their pivotal points, and adjustable stops to limit spring-induced movement of the loop spreaders. 120

6. In under thread-carrying mechanism for buttonhole sewing machines, an oscillat- 125

ing support, a plurality of loopers fixedly mounted theron, a plurality of spring-controlled loop spreaders pivotally mounted on the support, adjustable stops to limit spring-induced movement of the loop spreaders, and a needle-guard on the support between the loopers and below the path of movement thereof.

In testimony whereof, I have signed my name to this specification, in the presence 10 of two subscribing witnesses.

CHARLES A. DAHL.
